UNITED STATES PATENT OFFICE.

CARL GABRIEL LINDBOM, OF DOVER, NEW HAMPSHIRE.

CIGARETTE CASE.

Application filed March 3, 1922. Serial No. 540,695.

To all whom it may concern:

Be it known that I, CARL GABRIEL LINDBOM, a citizen of the United States, residing at Dover, in the county of Strafford and 5 State of New Hampshire, have invented certain new and useful Improvements in Cigarette Cases, of which the following is a specification.

The invention to be hereinafter described 10 relates to cigarette cases, and more particularly to cases for cigarettes marketed in a wrapping or package of paper or other material which is so pliable that the package is dependent on the presence of the cigarettes 15 therein to hold its shape.

When the user desires to obtain a cigarette from such a package, he usually tears open a portion of the wrapping at one end of the package, thereby enabling him to pull 20 a cigarette therefrom. After the first cigarette has been removed, the cigarettes remaining in the package are loose, and this looseness increases as succeeding cigarettes are removed from the package. The consequence 25 is that the cigarettes become displaced from their original parallel side-by-side relation, and the wrapping no longer is held in its original shape, but becomes dented or depressed inward and distorted. 30 As a result, a portion of the tobacco in the cigarettes is loosened and escapes from the ends of the cigarettes, and escapes from the package. When the opened package is returned into the pocket of the user, the tobacco 35 is liable to escape from the package into his pocket. Also, some of the cigarettes are liable to escape from the package into the pocket, and the cigarettes are liable to become bent and crumpled or broken so that 40 they are unfit for use.

The aim and purpose of the present invention, therefore, is to provide a simple cigarette case for the type of cigarette package referred to, whereby the package 45 may be maintained in its original shape until all of the cigarettes have been removed therefrom, and whereby the opening at the end of the package through which the cigarettes are removed may be normally closed by the 50 case cover so as to prevent escape of tobacco from the package.

With the aforesaid and other purposes in view, the character of the invention will be best understood by reference to the following description of one good form thereof

shown in the accompanying drawing, wherein:

Figure 1 is a perspective view of a cigarette case embodying the invention;

Fig. 2 is an end elevation of the case showing the method of inserting a package therein;

Fig. 3 is a vertical section through the case; and

Fig. 4 is a horizontal section through the 65 case.

Referring to the drawing, the case shown therein as one good form of the invention, comprises a top 1 and opposed sides 3 projecting therefrom and spaced apart so as 70 to receive a cigarette package 5 between them. The sides 3 may have a length substantially equal to the length of the cigarette package. The sides 3 have opposed inturned flanges 7 at one side of the case, 75 and similar opposed inturned flanges 9 at the opposite side of the case. The top and sides described, may be conveniently died out of sheet metal, and bent to the shape described.

An important feature of the invention relates to means for holding the package in the case. This means, in the present instance, comprises a tongue or member 11 located at one end of the case intermediate 85 the side flanges 9. This tongue, in the present instance, is a continuation of a plate 13 (Fig. 3) bent substantially at right angles to the tongue, and extending along the under side of the top and secured thereto by a 90 rivet 15 or other appropriate means. The tongue 11 may have opposed longitudinal marginal portions or flanges 17 curved or bent inward somewhat, said marginal portions being provided with series of notches 95 19 or other suitable frictional surface. These marginal portions 19 and the side flanges 9 overlap a substantial extent, and the inherent resilience of the tongue 11 is such that it tends to move outward to press 100 the marginal portions thereof against the side flanges. The top 1 may have a short lip 20 (Figs. 2 and 3) bent therefrom and extending a short distance along the tongue 11 to serve as a stop, as more fully herein- 105 after described.

The top 1 of the case is made short than the width of the case to leave an opening 21 through which the cigarettes may be removed from the package. This opening may 110

be provided with a cover 23 conveniently of sheet metal, and provided with hinge pins 25 entered through holes in the sides 3 adjacent the upper ends thereof, said pins being offset somewhat from the inner edge 27 of the cover. A leaf spring 29 (Fig. 3) conveniently an extension of the tongue carrying plate 13 referred to, has its free end in engagement with the inner edge portion of the cover. Opposed to the free end of the spring is a down-turned flange 31 formed on the top 1, and serving as a stop to limit opening movement of the cover. The upper portions of the sides 3 at the opening, may be cut away to present wings 33 for engagement with opposite edges of the cover.

When it is desired to open the cover, the front edge thereof is engaged by the hand 20 of the user, and rocked from its position shown in Fig. 3, to its position shown in Fig. 1. In the course of this movement of the cover, its rear edge will wipe down against the free end portion of the leaf 25 spring 29, thereby increasing the tension of the latter. When the cover is in open position, the spring will engage the inner edge thereof and hold the same in said position. When the cover is closed, the spring will engage 30 the inner side portion of the cover and press the same against the top flange stop 31 and hold the cover in said position.

The cigarette package of the type above referred to, has a paper band or wrapper 35, usually stamped with the name of the brand of the cigarette, and with pictorial and other printed matter. When it is desired to introduce a cigarette package into the case, the package is presented at the open base of the case and slid therein, as will be noted in Fig. 2. In the course of this movement, the tongue 11 will project between the wrapper and one side of the package, and said tongue will be sprung or flexed inward somewhat away from the side flanges 9. The consequence is that the wrapper will be frictionally gripped between the tongue and the side flanges 9, and will secure the package in the case. The 40 series of notches 19 in the marginal portions of the tongue will contribute to the frictional grip of the tongue on the wrapper. These notches may desirably have an inclination in respect to the longitudinal edges 45 of the tongue, thereby further to contribute to their securing effect.

It will be noted that the side of the casting intermediate the flanges 7 is open, but since the tongue is inserted between the 50 wrapper and the body of the package, it will not only prevent outward movement of the package through the open end of the case, but also will prevent outward movement of the package through the side opening between the flanges 7.

Since the tongue is located between the sides of the case, it will prevent the sides from flexing inward toward each other sufficiently to compress the package and increase the friction between the cigarettes therein. When the package is slid into the case, the edge 37 of the band or wrapper will come into engagement with the lip stop 20, and arrest the package at a point somewhat in from the top of the case. This will prevent the top from pressing on the end of the package and the cigarettes contained therein. The construction of the case is such that the cigarettes in the package do not experience either lateral or end pressure.

When it is desired to remove a cigarette from the case, the cover 23 is opened, and a portion of the top of the package exposed by the cover is torn away. Then a cigarette 85 at the cover opening 21 may be pulled from the package. If need be, this may be assisted by pressing the finger against the flexible bottom of the package exposed at the open base of the case.

When it is desired to remove another cigarette from the package, the case may be manipulated so as to allow the cigarettes to drop or gravitate toward the side of the package at the opening, so that the upper end of the cigarette will be exposed where it may be grasped and pulled from the package as before. Thus, successive cigarettes may be removed from the package in the case, and since the sides of the case do not press against the sides of the package, and the top of the case does not press against the ends of the cigarettes, the latter may also drop or gravitate toward the side of the package beneath the opening in the case upon proper manipulation of the latter.

The cigarette package may be quickly and easily inserted into the case, and the sides thereof will be protected by the case and prevented from collapsing inward. The tongue cooperating with the side flanges to clamp or grip the wrapper or band of the package, will prevent the latter from escape through the open side of the case opposite to the tongue, whereas, otherwise the package would be liable to escape through the open side, especially when the cigarettes have been nearly all removed from the package and no longer hold the sides of the package outward in their original form. The cover of the case will be normally closed, and thus will prevent any loose tobacco escaping from the ends of the cigarettes from falling out of the case.

The cigarette case is simple and cheap in construction, and desirable as an efficient protecting container for cigarette packages.

It will be understood that the invention is not limited to the specific embodiment.

ment shown, and that various deviations may be made therefrom without departing from the spirit and scope of the appended claims.

5. What is claimed is:—

1. A cigarette case comprising a top, opposed sides projecting from said top and spaced to receive a cigarette package between them, and a tongue projecting from said top intermediate said sides for insertion between the package and its wrapper, said sides having inturned flanges cooperating with said tongue to frictionally grip the wrapper and hold the package in the case.

10. 2. A cigarette case comprising a top, opposed sides projecting from said top and spaced to receive a cigarette package between them, and a tongue projecting from said top intermediate said sides and having frictional marginal portions, said sides having portions cooperating with said tongue for gripping the wrapper of the package to hold the latter in the case.

15. 3. A cigarette case comprising a top, opposed sides projecting from said top and spaced to receive a cigarette package between them, said sides having inturned flanges for engagement with sides of the package, and a tongue at one side of the case adjacent the side flanges thereat and cooperating with the latter to grip the wrapper of the package between them.

20. 4. A cigarette case comprising a top, opposed sides projecting from said top, a tongue cooperating with the sides to grip a portion of the wrapper of the cigarette package between them, and a stop at one end of said tongue to prevent the inner end of the package from engagement with the top of the case.

25. 5. A cigarette case comprising two spaced side walls having an open end therebetween through which a wrapped cigarette package may be inserted, a top plate at the opposite end said top plate having an opening provided with a movable cover through which cigarettes may be extracted, means to prevent the inner end of the package when in-

serted from engaging said top plate, and a tongue extending from said plate adapted to slip inside the wrapper of the package and guide the package into engagement with said means.

30. 6. A cigarette case comprising a top having an opening therein, opposed sides projecting from said top and adapted to receive a cigarette package between them, means frictionally to hold the package in the case, and a cover for said opening movable to expose ends of cigarettes at said opening.

35. 7. A cigarette case comprising a top, opposed sides projecting from said top for receiving a cigarette package between them, and a plate secured to said top having a tongue projecting therefrom for insertion between the body of the package and a portion of the wrapper thereof, said sides having portions cooperating with said tongue to frictionally grip the portion of the wrapper therebetween.

40. 8. A cigarette case comprising a top having an opening, opposed sides projecting therefrom and spaced to receive a cigarette package between them, a hinged cover for said opening, a plate secured to said top having a spring portion cooperating with the cover to hold the same in open and closed positions, and a tongue projecting from said plate between the sides of the casing and cooperating with the latter to grip a portion of the wrapper of the package.

45. 9. A cigarette case comprising a top, opposed sides projecting from said top for receiving a cigarette package between them, and a tongue projecting from the top between said sides for insertion between a side of the package and its wrapper.

50. 10. A cigarette case having a top, sides with an opening at one side of the case and an opening at the end of the case, and a tongue opposite the open side of the case for entrance between a side of a cigarette package and its wrapper on insertion of the package through the end opening.

CARL GABRIEL LINDBOM.
